UNITED STATES PATENT OFFICE

CHARLES F. RODIN, OF SAN FRANCISCO, CALIFORNIA

EMERGENCY SECTION FOR SHIPS

Application filed January 19, 1929. Serial No. 333,639.

My invention relates to improvements in emergency sections for ships, and it consists in the combinations, constructions and arrangements hereinafter described and 5 claimed.

An object of my invention is to provide an emergency section for ships that has accommodation for all of the people carried by the boat and enough storage space 10 for food and equipment to take care of the people until rescued. The section is made strong and is secured to the ship in such a manner that it will float free if the ship should sink. It also has means for permitting the section to be launched when the 15 ship has listed but not as yet sunk.

A further object of my invention is to provide a device of the type described that makes use of a roller chain for permitting 20 the section to easily slide off from the ship, either end of the chain being releasable from the section so as to have the chain permit the section to move, and subsequently to have the chain hang downwardly and 25 act as an anchor for the section. The listing of the boat aids in the launching of the section, whereas with the usual lifeboats the boats on the weather side cannot be readily launched.

30 Other objects and advantages will appear as the specification proceeds, and the novel features will be particularly pointed out in the appended claims.

My invention is illustrated in the accompanying drawing, in which

Figures 1 and 2 show perspective views of boats with the emergency sections in place;

Figure 3 shows a boat with a thirty-degree list, and further shows how the section is inclined so as to readily move into the water;

Figure 4 is a top plan view of the emergency section;

Figure 5 is a front elevation;

Figure 6 is an end elevation;

Figure 7 is a section along the line 7—7 of Figure 4; and

Figure 8 is a section along the line 8—8 50 of Figure 6.

In carrying out my invention, I show an emergency section at the position A on the boat 1. The boat shown in Figure 2 carries two emergency sections B, one fore and one aft. It is obvious that the sections may 55 be placed at any desirable point on the boat so as to not interfere with the normal use of the boat yet be ready to receive all of the people and carry them to safety in case of the sinking of the ship.

In Figure 3 I show a boat 2 as listing to an angle of thirty degrees. It will be seen that the lifeboats 3 on the right-hand side of the boat cannot possibly be launched without sliding down the side 4 of the boat. 60 This will cause the lifeboats to either upset or possibly be damaged before nearing the water. In the same Figure 3 I show an emergency section indicated at C. The section is made large enough to carry all 65 of the passengers, and it will be seen that the inclination of the boat will not interfere with the proper launching of the section but in fact will aid it.

I will now describe the particular construction of the section. Reference to Figure 4 shows that the section is rectangular in shape, although any other shape may be resorted to without departing from the spirit and scope of my invention. The section has a roof 5, a bottom 6, side walls 7, curved end walls 8, a railing 9 on the top wall, and an entrance hatch 10 (see Figure 3). The hatch may be closed, and this will 70 keep out water even though the waves dash entirely over the section. Of course, the section is made strong enough to withstand the buffeting of the waves and to safely carry all of the people until rescue comes.

The section is held in place by locking members that may be manually released. I further provide an automatic release should it be impossible to release the section before the ship sinks. The section is locked at each end and along each side. The locking mechanism at each end and side is identical, and therefore the description of one will suffice.

In Figure 4 I show the deck 11 of the boat. This deck carries an end plate 12 80

preferably having a length equal to the width of the section. The plate 12 is hinged at 13 to the deck, and its upper edges hingedly carry retaining members 14 (see Figure 4). The members 14 rest upon the top 5 of the section, and have openings 15 for receiving lugs 16 formed as extensions from the sides 17. Figure 4 shows two sides 17 as cooperating with each end 12. So long as the members 14 remain in the position shown, the plate 12 and sides 17 will be interlocked and the emergency section will be held in place.

I provide means for manually releasing the plate 12 from the sides 17. A lever 18 (see Figures 4 and 5) is rigidly connected to a cross shaft 19, the latter being mounted in bearings 20 carried by the top 5. At the ends of the shaft 19 I dispose lifting members 21.

These members underlie the members 14 as is clearly shown in Figure 7, and when the left-hand lever 18 is swung clockwise in Figure 5, the left-hand members 14 will be swung about their hinges 22 and will release the sides 17 from the end plate 12. The end plate 12 will swing about its hinge 13 as indicated by the dotted line in Figure 3, and the sides 17 will swing down upon the top 11. This will clear the deck for the movement of the section toward the left in Figure 5. If the boat has listed in the manner shown in Figure 3, the section will start to move when the left-hand end of the chain is released.

I have provided a roller chain between the emergency section and the deck 11 for permitting the ready movement of the section into the water. The rollers 23 are connected to each other by links 24 (see Figures 5 and 6). Either end of the chain may be released. This will permit the chain to hang downwardly from the opposite end after the section reaches the water, and the chain will act as an anchor. If the angle is not too steep, the section will be held in place by the chain until the end of the chain on the lowermost end of the section is released.

In Figure 8 I show a lever 25 that is secured to a rod 26, the latter being carried by bearings 27 that in turn are supported by the emergency section. The rod has hooks 28 and the lever has a similarly-shaped hook 29 that extends beneath the shaft 30 upon which the end set of rollers 23 are mounted. The lever 25 may be swung after the end 12 has been released, and this will free the end of the roller chain. This end of the chain will drop down upon the deck 11 and will permit the section to move freely thereover. After the section reaches the water, the chain will hang downwardly from the other end and will act as an anchor.

In case the boat sinks so rapidly as to prevent the actuation of either of the levers 18 or 25, the section will automatically re-

lease itself. It will be noted that the section will float upwardly away from the deck 11 should the boat sink, and this will lift the members 14 off from the lugs 16 for freeing the end plates 12 and the sides 17. The section may now float away independently of the boat.

It should be noted that the section will not move even though the retaining plates are freed. The chain must first have its lowermost end released before the section can move.

Although I have shown and described one embodiment of my invention, it is to be understood that the same is susceptible of various changes, and I reserve the right to employ such changes as may come within the scope of the invention as claimed.

I claim:

1. The combination with a boat, of a detachable floatable section, means for securing the section to the boat for preventing longitudinal as well as lateral movement of the section with respect to the boat, said means being manually operated for releasing said section from the boat when the section has a slight list due to the sinking of the boat and before its submerging.

2. The combination with a boat, of a detachable floatable section, means for securing the section to the boat, said means automatically releasing said section from the boat when the section starts to float due to the sinking of the boat, said securing means being manually actuated for launching the section.

3. The combination with a boat, of a detachable floatable section, means for securing the section to the boat for preventing longitudinal as well as lateral movement of the section with respect to the boat, said means being manually operated for releasing said section from the boat when the section has a slight list due to the sinking of the boat and before its submerging; said section being large enough to accommodate a large number of people and having a closed top for preventing water from entering the section.

4. The combination with a boat having a platform, of a detachable floatable section mounted on said platform, said section being launchable from said platform when the latter has a slight list, and a roller chain disposed between the platform and section for aiding in the launching, said chain being independent of said section, and means for holding the chain against movement, said means automatically freeing the chain upon the sinking of the boat.

5. The combination with a boat having a platform, of a detachable floatable section mounted on said platform, said section being launchable from said platform when the latter has a slight list, a roller chain disposed between the platform and section for

aiding in the launching, said chain having its ends secured to said section, and means for releasing either end of the chain for causing it to act as an anchor for the floating section.

6. The combination with a boat, of an emergency section carried by and being launchable from said boat, retaining members for said section and being hinged to the boat, manually controlled means for releasing said retaining members, said means automatically releasing said members as the section is raised by the incoming water.

7. An emergency section for ships closed on all sides and having a roller chain extending across the bottom of the section, the ends of said chain being secured to said section and preventing its movement until the chain is released.

8. An emergency section for ships closed on all sides and having a roller chain extending across the bottom of the section, either end of said chain being releasable for causing the chain to act as an anchor for the floating section.

9. The combination with a boat, of an emergency section carried thereby, retaining members hingedly carried by said boat and abutting the ends and sides of the section, locks carried by certain of said members and engaging with the others for securing all of them in position, said locks being manually released or released by the section when the latter is floated.

10. The combination with a boat, of an emergency section carried by and being launchable from said boat, retaining members for engaging with the sides of said section, said means automatically releasing said members as the section is raised by the incoming water.

11. An emergency section for ships closed on all sides and having a roller chain extending across the bottom of the section, the ends of said chain being secured against movement and preventing movement of the section until the chain is released.

12. An emergency section for ships closed on all sides and having a roller chain extending across the bottom of the section, either end of said chain being releasable for causing the section to roll from a ship on which it is supported.

13. The combination with a boat, of an emergency section carried thereby, retaining members hingedly carried by said boat and abutting the ends and sides of the section, locks carried by certain of said members and engaging with the others for securing all of them in position, said locks being released by the section when the latter is floated.

14. The combination with a boat, of an emergency section carried thereby, retaining members hingedly carried by said boat and abutting the ends and sides of the section,

locks carried by certain of said members and engaging with the others for securing all of them in position, said locks being manually released or released by the section when the latter is floated, a roller chain extending across the bottom of the section, and manually releasable means securing the ends of the chain to the section.

15. The combination with a boat, of an emergency section carried thereby, retaining members hingedly carried by said boat and abutting the ends and sides of the section, locks carried by certain of said members and engaging with the others for securing all of them in position, said locks being manually released or released by the section when the latter is floated, a roller chain extending across the bottom of the section, and manually releasable means securing the ends of the chain to the section, either end of said chain being releasable for causing the chain to act as an anchor for the section while the section floats.
